TEXTILE YARN

Joseph McGowan, North Tiverton, R. I.

Application January 16, 1934, Serial No. 706,824

15 Claims. (Cl. 117--52)

My present invention relates to the textile art, and has particular reference to an ornamental and novelty yarn suitable for the manufacture of textile cloth and fabrics.

5 The novelty yarns heretofore used have included threads of different colors and different thicknesses, or both. In order to provide a textile yarn of distinctive appearance, I have devised a series of novelty yarns which utilize enlarged portions, such as splashes, slubs, or flakes, and raised portions such as nubs, together with 10 novelty twists such as ratine.

15 My improved novelty yarns consist of different arrangements of a base yarn having spaced sections of different thicknesses which may be combined with threads of different colors which are preferably twisted to form spaced nubs, the yarn if desired also having a selective ratine twist.

With the above and other advantageous features in view, my invention consists of new forms 20 of yarns more fully disclosed in the detailed description following, in conjunction with the accompanying drawings, and more specifically defined in the appended claims.

25 In the drawings,

Fig. 1 represents a yarn containing spaced splashes;

Fig. 2 represents a yarn having spaced slubs;

30 Fig. 3 discloses a twisted yarn having spaced flakes;

Fig. 4 is similar to Fig. 3, but discloses a type designated as French flake;

Fig. 5 represents a yarn with spaced nubs;

35 Fig. 6 is generally similar to Fig. 5, the yarn including nubs with a binder;

Fig. 7 is a yarn having a fine ratine twist;

Fig. 8 represents a yarn having a coarse ratine twist;

40 Fig. 9 discloses splashes with nubs, two colors being preferably used;

Fig. 10 represents a flake yarn with single and double nubs; three colors are preferably used;

Fig. 11 represents a flake yarn with double nub, the nubs being of different colors;

45 Fig. 12 represents a flake yarn with nubs between flakes;

Fig. 13 represents a long spaced flake yarn, with two nubs of different color on each flake;

50 Fig. 14 is similar to Fig. 13 with three nubs on each flake, a preferred arrangement including two cotton nubs of different color and one tinsel nub;

55 Fig. 15 is similar to Fig. 12, three nubs being provided between flakes, the nubs being of different colors;

Fig. 16 is a novelty yarn with flakes, nubs on the flakes, and a ratine twist between flakes; and

Fig. 17 is a section of novelty cloth woven with one form of the improved novelty yarn.

5 My improved yarn arrangement is formed by utilizing flakes, or the equivalent splashes and slubs, with nubs positioned selectively on or between the flakes, together with a ratine twist wherever desired. To this end, I have positioned a desired number of nubs, either one, two, or 10 three, on a base yarn which has spaced thicknesses, hereinafter termed flakes, and have further utilized a ratine effect wherever desired to increase the ornamental appearance of the yarn and of the textile fabric or cloth made therefrom. 15 In making the novelty yarns, colors may be used as desired for the flakes, as well as for the nubs, in order to give different ornamental appearances to the yarn, and to the fabric woven therefrom.

20 Referring to the drawings, the yarn 29 shown in Fig. 1 includes a core 28 twisted at intervals to provide a plurality of spaced flakes 22. If desired, a binder thread 23, see Fig. 2, may be used, to form a twist around the core, and may be additionally twisted to provide a ratine effect 24 between the flakes, see Fig. 3; if the twist is amplified, as indicated in Fig. 4, a French flake type is obtained having coarse ratine effects 26 between bunched flakes 28. Various ornamental yarns may thus be provided by utilizing flakes and binder 30 threads.

25 Referring now to Fig. 5, a novel yarn 27 comprises a core 26 about which a binder thread is twisted to provide spaced nubs 29, the twist being arranged, if preferred, see Fig. 6, to provide a 35 ratine effect 30 between the nubs. Or the yarn 31, see Figs. 7 and 8, may comprise a core 32 with a binder 33 which is twisted to obtain a fine ratine effect 34, or a coarse ratine effect 35. An ornamental yarn may thus be obtained by using binder 40 threads to provide spaced nubs, or to obtain a ratine effect.

35 These arrangements are preferably utilized in selected combination; thus the yarn 36 in Fig. 9 has spaced flakes 37, and spaced nubs 38 of different colors on the flakes, and twist 39 between the flakes; whereas the yarn 40 in Fig. 10 has double nubs 41, and single nubs 42 on the flakes 43 with twist 44 between the flakes, the nubs being of contrasting colors. The yarn 45 in Fig. 11 has 50 double nubs and longer spacing between the flakes, whereas the yarn 46 in Fig. 12 has double nubs between the flakes instead of on the flakes. The combination of flakes and nubs are thus productive of a series of novelty yarns.

50

55

A yarn 47 is disclosed in Fig. 13, having a long spacing between the flakes; Fig. 14 shows a yarn 48 having three nubs 49, 50, 51 on spaced flakes 52, the nubs 49, 51 being of binder thread of different colors and the nub 50 of tinsel thread, with twist 53 between the flakes. The yarn 54, see Fig. 15, is generally similar, but the nubs are positioned between the flakes, and the yarn 55, see Fig. 16, has very long spacing between the flakes 56 which have a single nub 57 mounted thereon, a ratine effect 58 being provided between adjacent flakes. The combination of flakes, nubs, and ratine effects are thus productive of a different series of novelty yarns.

The cloth 59 woven from one form of novelty yarn described is depicted in Fig. 17, and includes an irregular arrangement of colored nubs 60 and flakes 61.

The selective arrangements hereinbefore described thus permit obtaining a multiplicity of distinctive novelty yarns to suit requirements for any type of novelty fabric, as the materials forming the base thread and the nubs, the colors of the materials, the spacing of the splashes and nubs, and the use of a ratine effect, may be varied as desired within the spirit and the scope of the invention as defined in the appended claims.

I claim:

1. A novelty yarn comprising a core having spaced flakes and a thread twisted therearound, the twisting being irregular and forming spaced nubs selectively positioned on said core.
2. A novelty yarn comprising a core having spaced flakes and a thread twisted therearound, the twisting being irregular and forming spaced nubs between the flakes.
3. A novelty yarn comprising a core having spaced flakes and a thread twisted therearound, the twisting being irregular and forming spaced nubs on the flakes.
4. A novelty yarn comprising a core having spaced flakes and a plurality of threads twisted therearound, the twisting of said threads being irregular and forming spaced nubs selectively positioned on said core.
5. A novelty yarn comprising a core having spaced flakes and a plurality of threads twisted

therearound, the twisting of said threads being irregular and forming spaced nubs between the flakes.

6. A novelty yarn comprising a core having spaced flakes and a plurality of threads twisted therearound, the twisting of said threads being irregular and forming spaced nubs on the flakes.

7. A novelty yarn comprising a core having spaced flakes thereon and a plurality of threads twisted therearound and forming spaced nubs selectively positioned on said core, said yarn having a ratine twist between the flakes.

8. A novelty yarn comprising a core having spaced flakes and a plurality of threads twisted therearound, said threads forming spaced nubs between the flakes, said yarn having a ratine twist between the flakes.

9. A novelty yarn comprising a core having spaced flakes and a plurality of threads twisted therearound, said threads forming spaced nubs on the flakes, said yarn having a ratine twist between the flakes.

10. A novelty yarn comprising a core with spaced flakes and a thread twisted about said core, the twisting being irregular to provide a nub on each flake.

11. A novelty yarn comprising a core with spaced flakes and a thread twisted about said core, the twisting being irregular to provide a nub on each flake, said yarn having a ratine twist between said flakes.

12. A novelty yarn comprising a core with spaced flakes and a plurality of threads twisted about said core, the twisting of each thread being irregular and forming a nub between adjacent flakes.

13. A novelty yarn comprising a core with spaced flakes and a plurality of threads twisted about said core, the twisting of said threads being irregular and forming adjacent nubs on said flakes.

14. A textile cloth woven from novelty yarn having spaced flakes and spaced nubs.

15. A textile cloth woven from novelty yarn having spaced flakes and spaced nubs, the yarn having a ratine twist between the flakes.

JOSEPH McGOWAN.
